PONTUS OSTENBERG, OF LOS GATOS, CALIFORNIA.

INTERNAL-COMBUSTION ENGINE.

1,137,887.

Specification of Letters Patent.

Patented May 4, 1915.

Application filed February 2, 1914. Serial No. 815,892.

To all whom it may concern:

Be it known that I, PONTUS OSTENBERG, a citizen of the United States, residing at Los Gatos, in the county of Santa Clara and 5 State of California, have invented a new and useful Internal-Combustion Engine.

My invention relates to internal combustion engines.

One object of my invention is to provide 10 an internal combustion engine in which a mass of liquid is used as a piston, the same being driven out of the cylinders under pressure of gas explosion and caused to revolve in a circular chamber, and in which the 15 kinetic energy of said revolving liquid is utilized to operate a driving shaft.

Another object of my invention is to produce 20 an internal combustion engine in which a revolving, pulsating mass of liquid in a circular chamber is utilized to supply the explosion chambers with oil, air, or an explosive mixture, said liquid acting under pressure of gas explosion.

Another object is to produce an internal 25 combustion engine in which a revolving, pulsating mass of liquid in a circular chamber is utilized to draw fluid into said circular chamber and discharge the same therefrom, said revolving liquid acting under pressure 30 of gas explosion.

Another object of my invention is to produce 35 an internal combustion engine that may be economically constructed, simple in operation, efficient and durable, and one which may be adapted to any purpose where power is required.

With these and other objects in view, the 40 present invention consists in the combination and arrangements of parts as will be hereinafter more fully described and particularly pointed out in the appended claims, it being understood that changes in the specific structure shown and described 45 may be made within the scope of the claims without departing from the spirit of the invention.

In the drawings forming a part of this 50 specification and in which like numerals of reference indicate similar parts in the several views, Figure 1 is a front elevation of my internal combustion engine. Fig. 2 is a sectional view on line A—A of Fig. 1. Fig. 3 is an enlarged sectional view on line B—B of Fig. 2. Fig. 4 is a vertical cross

section of another embodiment of my invention. 55

To enable others skilled in the art to understand my invention, I will proceed to describe the manner in which I have carried it out. 60

In the accompanying drawings 1 is the main body portion of my internal combustion engine, made circular in plan of the required diameter and of the required thickness of walls. The same may be made of 65 boiler iron and riveted together in sections, or the same may be made of cast metal having one or more cylinders as shown at 2 and 2^a, attached thereto. Driving shaft is shown at 3 having a packing nut shown at 3^a 70 and a fly wheel shown at the top thereof at 3^b. Keyed near the lower end of said shaft is disk wheel 4. The extreme lower end of said shaft 3 is held in place by step bearing 3^c, bolted to said body portion 1 by bolts 1^a. 75 Said disk wheel 4 is made of cast iron or any other suitable material carrying at its outer circumference a plurality of circular disks 5, said disks being made of sheet metal of the required width and thickness, and are 80 circular in form, the same being fastened to wheel 4 with the required space apart one on top of another, and are driven by the liquid discharged through ports 6, said ports being so constructed as to direct the 85 fluid in a circular course around chamber 22 from explosion chamber 7. Near the top of cylinders 2 and 2^a and at one side thereof are hot-balls 8 connecting with explosion chambers 7 by ports 9. The lower part of 90 said ports 9 is made dishing in shape for the purpose of retaining a portion of the oil which vaporizes by the heat from hot-balls 8 just ahead of the compression. At the top of cylinders 2 and 2^a and connecting 95 with explosion chambers 7 are located air intake valves 10. The amount of air admitted through said valves being governed by springs 11. Near the top of cylinder 2 and connecting with explosion chamber 7 100 is cartridge chamber 13. Vacuum pump connection is shown at 14, plug valve is shown at 15 for the purpose of closing said connection after the vacuum is formed. A distance below the top of said cylinders 2 105 and 2^a are shown offsets in which a plurality of exhaust valves 16 are shown. Said valves have an upper seat shown at 16^a, and a

lower seat shown at 16^b, and are balanced in such a manner as to allow the exhausted gases to escape until the liquid reaches and closes said valves, said liquid passing on 5 up to compression. Liquid valve 17 is for the purpose of admitting liquid to cylinders 2 and 2^a, gage valve 18 is for the purpose of designating the height of liquid in said cylinders 2 and 2^a. Air intake is shown 10 at 19, air intake valves are shown at 20 closed by spring 21. Disk wheel chamber is shown at 22, air storage chamber is shown at 23. Check valve admitting air from chamber 22 to chamber 23 is shown at 24. 15 Air pipes leading from air chamber 23 to intake valves 10 are shown at 25.

Oil supply cylinders are shown at 26 attached and connecting with cylinders 2 and 2^a by ports 27. On the inside of said oil 20 supply cylinders are valves 28 resting on valve seats 29. On the upper end of valve stem is float 30, which is for the purpose of opening and closing said valves 28 as the liquid is driven in and drawn out by each 25 explosion in chamber 7 through ports 27. At the side and near the top of said oil supply cylinders 26 are oil intake connections 31 leading to a tank of oil supply not shown, said connections 31 being supplied with ball 30 valves 32. At the top of said oil supply cylinders are chambers 33, said chambers being supplied with ball valves 34. Connected to said chambers 33 are oil pipes 35 leading to ports 9 in front of hot-balls 8. 35 Gage valves are shown at 35^a attached to pipes 35 which are for the purpose of regulating the amount of oil fed to ports 9. Lower liquid outlets leading from chamber 22 to cylinders 2 and 2^a are shown at 36. 40 Valves 37 are for the purpose of preventing liquid from passing from cylinders 2 and 2^a through liquid outlets 36 to chambers 22. Lever 38 pivoted to casting 39 and connected to valve stem 11^a and firing rod 40 is for the 45 purpose of holding valve 10 up against its seat while the vacuum is being formed in compression chamber 7 and also for the purpose of firing cartridge 41 in chamber 13. Fig. 4 is another embodiment of my 50 internal combustion engine, with driving shaft 3 and disk wheel 4 removed from chamber 22. The explosion in chamber 7 causes the liquid to be driven through port 6, the angle of said port being such as to direct the liquid 55 in a circular course around chamber 22, when the centrifugal force of said liquid traveling around said chamber 22 forces said liquid to ascend in said cylinder 2 it thereby causes a suction in the center of said chamber 22 and draws in more liquid through pipe 42 and valve 43, and the following explosion drives the surplus liquid out through valve 44 into discharge pipe 45 thus drawing in and discharging fluid at every pulsation 60 of the engine.

The operation of my internal combustion engine is as follows;—Chamber 22 and cylinders 2 and 2^a are filled with liquid through liquid valve 17 up to a level with liquid valve 18. A cartridge 41 is inserted in cartridge chamber 13. A vacuum pump is now attached to plug valve 14 and the air exhausted from cylinder 2 which draws in a charge of air and oil in compression chamber 7 of cylinder 2^a, air being prevented 70 from entering cylinder 2 through valve 10 by pressing down on the handle of lever 38. Cartridge 41 is now fired, thus driving the fluid in chamber 2 through port 6 against, or rather between, disks 5 into chamber 22, 75 the angle of port 6 being such as to direct the fluid in a circular course around the chamber 22 thus causing disks 5 to revolve and causing shaft 3 and pulley wheel 3^b to rotate. The same explosion drives a portion 80 of the liquid through passage 27 and valve 28 into the oil supply chamber 26 to float 30, this chamber being previously supplied with oil through oil supply pipe 31. The sudden discharge of liquid into said chamber drives 85 the required amount of oil out through the discharge pipe 35 into the receiver in port 9 of cylinder 2^a. The centrifugal force of the revolving liquid in chamber 22 forces it outwardly into cylinders 2 and 2^a thus tending 90 to form a vacuum in chamber 22 and consequently drawing in air through valve 19. As the liquid rises in cylinder 2 valves 16 are forced open sufficiently to allow the exhaust to pass out therethrough, but are 95 closed by the liquid when the same reaches them and stay closed until the force of the ensuing explosion is spent. When the liquid passes the level of valves 16 it compresses the air forced in through valves 10 after the 100 previous explosion, the compressing air driving the oil in the receiver in port 9 of cylinder 2^a into the hot-ball 8 where it is vaporized and exploded when the proper compression is reached. The revolving 105 liquid in chamber 22 not only drives shaft 3, but also through its pulsating movement, draws in air through valve 19 and discharges the same into chamber 23 where it is fed into explosion chamber 7 through pipes 110 25 and valves 10, alternate in action.

In this preferred embodiment of my invention I have described the engine as operating with separate air and oil supplies, but it will work equally as well when a gas and air mixture is drawn in from a carbureter through valve 19 and fed to chambers 7 as described, in which case the oil supply chambers 26 would not be used. In another embodiment of my invention the oil supply 120 chambers may be used as described and the carbureter dispensed with, the pulsating motion of the revolving liquid being used to draw in and discharge a liquid as described 125 with reference to Fig. 4.

The foregoing being a general description of the operation of my invention, I will now proceed to explain in detail certain parts of the operation and the principle involved, referring to the preferred embodiment illustrated in Figs. 1, 2 and 3, it being assumed that the engine has been started and is in full operation, water being used. First, as to the action of the water in chamber 22, said water being driven at a high velocity by alternate explosions in the upper part of cylinders 2 and 2^a. Cylinders 2 and 2^a and chamber 22 are so proportioned that after the explosion in one cylinder, and after the water has been driven out of said cylinder and has just started to enter the other cylinder, chamber 22 is nearly full of a rapidly revolving body of water. The centrifugal force of this rapidly revolving body of water of course tends to throw said water against the outer side wall of chamber 22, which is circular in form, and consequently leaves a comparatively small and more or less cylindrical air space surrounding shaft 3 in the center of chamber 22. The amount of water used should be such that no large quantity could work into chamber 23, though a means would be provided for draining said chamber 23 in case water did enter therein. Now as the centrifugal force of the water carries it through ports 6 and passages 36 into cylinders 2 and 2^a, the central air space expands. As this air space grows larger and larger on account of the receding water, the density of the air contained therein must decrease and continue to decrease until the water uncovers air intake 19 when a charge of air or gas will be drawn in to fill the partial vacuum thus formed. At this point the explosion occurs in the second cylinder, driving the body of water back into chamber 22 through port 6 at the necessary angle to make it revolve therein. This comparatively large body of water entering chamber 22 again causes the central space to contract, and consequently a large portion of the charge of air or gas in said central space must pass through valve 24 into chamber 23. A portion of the kinetic energy imparted to disk-wheel or rotor 4 by the water entering chamber 22 through ports 6 will be consumed in imparting centrifugal force to the revolving body of water and thus aid in securing the compression required. It will thus be seen that the revolving body of water in chamber 22 has two functions, viz,—operating the disk-wheel or rotor 4 and keeping chamber 23 supplied with air or gas under pressure; and the water forced into cylinders 2 and 2^a by centrifugal force has three functions, viz,—exhausting the burnt gases from said cylinders, compressing the explosive charges in said cylinders, and oper-

ating the oil devices. Now, when the explosion has taken place in a cylinder and the water driven out thereof, the burnt gases exhaust to atmospheric pressure through valves 16 properly balanced for that purpose and normally resting upon their upper seats 16^a. As the water rises in the cylinder by virtue of the centrifugal force imparted to it as described above, it drives out more of the burnt gases through valves 16 until said water reaches them and closes them upon their lower seats 16^b, passing on up to compression. The air or gas stored under compression in chamber 23 passes through pipes 25 and valves 10 into explosion chambers 7 when the burnt gases are sufficiently exhausted therefrom and practically fills that portion of the cylinders above valves 16 until compressed by the returning water. The force of an explosion at the moment of explosion is estimated to be about four times the compression, therefore if the rising water compresses the charge to 100 pounds per square inch and the charge then exploded, said water will be driven out with a force of about 400 pounds per square inch. It will thus be seen that, the charge being the same each time the compression will be greater and greater, and the water will be driven out more and more rapidly and with greater and greater force, so that in order to keep the speed down where required the quantity of oil fed to ports 9 is regulated by valves 35^a, thus decreasing the richness of the explosive charge. 100

Having thus described my invention, what I claim as new and desire to secure by Letters Patent, is:—

1. In an internal combustion engine, the combination of a body portion circular in plan having one or more cylinders attached thereto, a driving shaft and means of rotating said shaft in said body portion, a fly wheel attached to the upper end of said shaft, a disk wheel keyed near the lower end of said shaft, a step bearing at the lower end of said shaft, means of attaching said step bearing to said body portion, a plurality of circular disks, means for fastening said disks to said disk wheel, means for discharging liquid through said disks, an explosion chamber in each cylinder, means for exploding the gases in said explosion chambers, a port dishing in the lower part thereof communicating with each of said explosion chambers and connecting the same with its respective explosion means, air intake valves and means for operating said valves, a cartridge chamber, means for attaching a vacuum pump to said explosion chamber, as 125 and for the purpose described.

2. In an internal combustion engine, the combination of a body portion having one or more cylinders attached thereto, each cylinder having an offset in which a plurality 130

of exhaust valves are set, said exhaust valves having upper and lower seats, a compression chamber formed in the upper portion of each cylinder and above said exhaust valves in which the gases are compressed and exploded, means for the admission of liquid to said cylinders, a gage valve designating the height of liquid in said cylinders, air intake valves, a disk wheel chamber adapted to inclose a disk wheel, air storage chamber above and attached to said disk wheel chamber, a valve admitting air from said disk wheel chamber to said air storage chamber, as shown and described.

15. 3. In an internal combustion engine, the combination of a body portion having one or more cylinders attached thereto, each of said cylinders having an explosion chamber formed in the upper portion thereof, a disk wheel chamber formed in said body portion, an air storage chamber attached to said body portion, air pipes leading from said storage chamber to air intake valves, oil supply cylinders and means for supplying oil through 20 said cylinders to said explosion chambers, a float connected with the valves in said oil supply cylinders, pipes leading from said oil supply cylinders to said explosion chambers, valves in said pipes to regulate the supply of 25 oil to said explosion chambers, lower liquid outlets leading from said disk wheel chamber to said cylinders, means for preventing liquid from passing through said lower liquid outlets from said cylinders, means for holding the air inlet valves in place, as and 30 for the purpose described.

4. In an internal combustion engine, the combination of a central chamber adapted to contain a revolving liquid, auxiliary chambers positioned about the periphery thereof, said central chamber having ports communicating with each of said auxiliary chambers at such an angle as to direct a liquid passing from said auxiliary chambers to 40 said central chamber around the periphery thereof, each of said auxiliary chambers having a conduit communicating with said central chamber and an inlet valve adapted to permit the passage of liquid from said 45 conduit into said auxiliary chamber, substantially as shown and described.

5. In an internal combustion engine, the combination of a central chamber adapted to contain a revolving liquid, auxiliary chambers positioned about the periphery thereof, said central chamber having ports communicating with each of said auxiliary chambers at such an angle as to direct a liquid passing from said auxiliary chambers 55 to said central chamber around the periphery thereof, each of said auxiliary chambers having a conduit communicating with said central chamber and an inlet valve adapted to permit the passage of liquid from said 60 conduit into said auxiliary chamber, said

central chamber being circular in plan, of greater diameter than depth, and so proportioned with relation to said auxiliary chambers that when said revolving liquid is increased or diminished in quantity therein by 70 reason of said liquid passing from or to said auxiliary chambers an increase or reduction of pressure is provided on a fluid contained in the central part of said central chamber, a valve controlled inlet for permitting the 75 passage of fluid into the central part of said central chamber upon reduction of pressure of a similar fluid contained therein, and a valve controlled outlet for permitting the passage of fluid from the central part of 80 said central chamber upon the increase of pressure on said fluid, substantially as shown and described.

6. In an internal combustion engine, the combination of a central chamber adapted to 85 contain a revolving liquid, auxiliary chambers positioned about the periphery thereof, said central chamber having ports communicating with each of said auxiliary chambers at such an angle as to direct a liquid passing 90 from said auxiliary chambers to said central chamber around the periphery thereof, each of said auxiliary chambers having a conduit communicating with said central chamber and an inlet valve adapted to permit the 95 passage of liquid from said conduit into said auxiliary chamber, an explosion chamber formed in the outer end of each auxiliary chamber, said central chamber being circular in plan, of greater diameter than depth, 100 and so proportioned with relation to said auxiliary chambers that when said revolving liquid is increased or diminished in quantity therein by reason of said liquid passing 105 from or to said auxiliary chambers an increase or reduction of pressure is provided on a fluid contained in the central part of said central chamber, a valve controlled inlet for permitting the passage of fluid into the central part of said central chamber upon 110 reduction of pressure of a similar fluid contained therein, a valve controlled outlet for permitting the passage of fluid from the central part of said central chamber upon the increase of pressure on said fluid, a compression chamber adapted to receive said expressed fluid, and valve controlled conduits for introducing said expressed fluid from said compression chamber to each of said 115 explosion chambers, and a driving shaft and rotor revolubly mounted in said central chamber adapted to be driven by said revolving liquid, substantially as shown and described.

7. The combination with an internal combustion engine of the class described having an explosion chamber and a reciprocating liquid contained therein, of an oil supply cylinder communicating with the liquid in said engine, a float valve operatively posi- 125 130

tioned in said oil supply cylinder, said oil supply cylinder being provided with a valve controlled oil inlet and a valve controlled oil outlet, and a conduit connecting said cylinder to the explosion chamber of said engine having a controlling valve positioned therein.

In testimony whereof I affix my signature in presence of two subscribing witnesses.
